Iwan Podobiedoff
By (and Attorney)

UNITED STATES PATENT OFFICE.

IWAN PODOBIEGOFF, OF PETROGRAD, RUSSIA.

WELL-CASING HEAD.

1,272,312.

Specification of Letters Patent.

Patented July 9, 1918.

Application filed February 2, 1916. Serial No. 75,751.

To all whom it may concern:

Be it known that I, IWAN PODOBIEGOFF, subject of the Czar of Russia, residing at Chornaia Retchka, 49, Petrograd, Russia, 5 have invented certain new and useful Improvements in Well-Casing Heads, of which the following is a specification.

The object of this invention is to provide means for washing through with slime the 10 bore-end of a well in sinking the latter after the well known rope boring system, so that the boring process may be greatly accelerated, without modifying in any way the usual operations necessitated by the rope 15 boring system. The said means consists of a cap or hood adapted to be removably secured to the upper end of the working tubular column or pipe and forming a chamber which communicates with this pipe and 20 is connected with the slime pressing pump.

In the drawing, Figure 1 shows a top view of the hood according to my invention, one half of the cover being swung away. Fig. 2 is a sectional elevation of the hood.

25 Fig. 3 is a detail sectional view of an interiorly-grooved bush comprised in the invention.

A hood 1 having a branch 2 to be connected to the slime pressing pump, is mounted on the upper end of the working pipe 18, 30 preferably by means hereinafter described. This hood is closed hermetically at the top by a cover 3, in the center of which a stuffing box 4 is inserted having a ball head 5, 35 inside which stuffing box reciprocates a tube 6; this latter tube, fastened firmly on the boring rope 7, protects it from wear and at the same time prevents the slime delivered into the hood for washing the well from escaping around the rope.

40 For rapidity and convenience in the periodical examination of the boring tool and replacing the same, the cover 3 is adapted to be opened in two halves, the pin 8 of the hinge being fastened firmly to the body of the hood 1. The upper edge of the hood 1 has a small projecting flange and the cover 3 is provided at its lower peripheral edge with an annular flange 9, which is recessed 45 on its inner side, so as to fit over the upper edge of the hood when the cover 3 is closed. To make a tight joint a rubber gasket 10 is placed in the recess of the flange 9 in both 50 halves of the cover. On closing the cover 55 3 both its halves are firmly connected to-

gether by means of a rocking latch 11, provided with a locking screw 12.

In the center of the cover 3 (in both halves of same) a ball seat is formed for the ball head 5 of the stuffing box 4, this ball head 5 being provided in view of the fact that the boring rope, besides having longitudinal reciprocating movements when working, also oscillates slightly sidewise. As stated above, a tube 6, about 12 feet long, 60 passes through the stuffing box 4 and can move freely in it along its entire length. This tube is screwed at its upper end into the socket 13, the latter having a taper thread at its upper end, by means of which 65 it engages with a bronze, babbitt, bush 14, consisting of two halves grasping the boring rope 7. The recess in the bush halves is provided with spiral grooves which are in strict 70 accordance with the curls of the rope. Thus, 75 when the said socket 13 is screwed into the bush 14 its halves grasp the rope tightly and fasten the tube 6 on it.

In the arrangement illustrated the hood 1 is fastened on the top of the working pipe 80 18 by means of a divided ring 15 pivoted on the lower part of the pin 8 and provided with inner circumferential grooves 16 enclosing elastic gaskets 17. On the two halves of the ring 15 being connected and 85 tightened together by means such as a latch 11 or the like, the hood is firmly secured to the upper end of the pipe. At the same time the recessed flange 9 on the ring engages over the flange on the lower edge of 90 the hood.

The use of such a slime hood affords the 95 possibility of applying slime washing of the bore-end of the well to the widely known and practised system of rope boring, which system, as is known, enables the work to be greatly accelerated. At the same time all the manipulations of rope boring remain without change, as after having unscrewed the bush 14 and opened the cover 3 and 100 the ring 15 (which with the present arrangement of them is attained very rapidly—by throwing back the latches 11), the tool with the rope may be raised from the well quite freely and any tool or catching device may 105 also be easily lowered into the well. While during the work of sinking, when the beam rises and falls the rope moves freely, together with the tube 6 set on it, in the stuffing-box 4, without changing the normal 110

method of work. The tube 6 is selected of such length as to permit the full length of the operating screw to be utilized with the utmost rise of the beam. The ball-shaped 5 form of the stuffing-box head 5 admits small rocking movements of the tube 6 and, therefore, of the boring rope also in all directions. At the same time the slime hood remains closed all the time and the slime 10 pumped through it by the pump is delivered continuously along the working pipe 18 to the bore-end of the well, thereby washing it, rises in the space around the pipe and carries with it the borings obtained by the 15 chisel, and overflows over the brim of the well to the slime shed.

What I claim is:

1. In a rope-boring, well-sinking apparatus, the combination, with the inner or working pipe; of a hood adapted to removably rest on the upper end of said pipe and provided with an inlet for washing-fluid, said hood having its top and bottom edges turned laterally outward and also having an exteriorly-located vertical pivot securely attached to its body and projecting at opposite ends above and below the edges of said body; a two-part ring having its members pivoted at one end to the lower end of said pivot and adapted to encircle said pipe when closed together and to engage said hood to connect the latter to the pipe; a two-part cover for the top of said hood having its members pivoted at one end to the upper end of said pivot and adapted when closed together, to engage said hood so as to retain the cover in place thereon; and devices for fastening together the free ends of the ring and cover members; said cover members being provided with mating openings through which the boring rope passes, and both said cover members and said ring members being adapted to be opened or spread apart to disengage them from the hood and to permit the hood, ring and cover to be removed as a unit from the pipe.

on said hood; and means for fastening the 45 free ends of the cover members together in closed position; said cover members being provided with mating openings through which the boring rope passes, and both said 50 cover members and said ring members being adapted to be opened or spread apart to disengage their flanged ends from the out-turned edges of the hood and to permit the hood, ring and cover to be removed bodily as a unit from the pipe. 55

2. In a rope-boring, well-sinking apparatus, the combination, with the inner or working pipe, of a hood adapted to removably rest on the upper end of said pipe and provided with an inlet for washing fluid, said hood having an exteriorly-located vertical pivot securely attached to its body and projecting at opposite ends above and below the edges of said body; a two-part ring having its members pivoted at one end to the lower end of said pivot and adapted to encircle said pipe when closed together and to engage said hood to connect the latter to the pipe; a two-part cover for the top of said hood having its members pivoted at one end to the upper end of said pivot and adapted when closed together, to engage said hood so as to retain the cover in place thereon; and devices for fastening together the free ends of the ring and cover members; said 65 cover members being provided with mating openings through which the boring rope passes, and both said cover members and said ring members being adapted to be opened or spread apart to disengage them 70 from the hood and to permit the hood, ring and cover to be removed as a unit from the pipe. 75

In testimony whereof I affix my signature.
IWAN PODOBIEDOFF.
